Primary Examiner — Susan E Krakower*Assistant Examiner* — Michelle M Reeves(74) *Attorney, Agent, or Firm* — Heslin Rothenberg Farley & Mesiti P.C.(57) **CLAIM**

The ornamental design for a seat, as shown and described.

DESCRIPTION

FIG. 1 is a front left perspective view of a seat according to the new design;

FIG. 2 is a rear right perspective view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a top view thereof; and,

FIG. 8 is a bottom view thereof.

The broken lines in the drawings illustrate portions of the seat and form no part of the claimed design.

1 Claim, 8 Drawing Sheets(56)
